UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

FILLED-BAG-SEWING MACHINE.

1,240,095.

Specification of Letters Patent. Patented Sept. 11, 1917.

Application filed May 4, 1914. Serial No. 836,320.

To all whom it may concern:

Be it known that I, DUDLEY S. SEYMOUR, a citizen of the United States, residing at Oak Park, in the county of Cook and State 5 of Illinois, have invented certain new and useful Improvements in Filled-Bag-Sewing Machines, of which the following is a description, reference being had to the accompanying drawing and to the figures of reference marked thereon.

The invention relates to new and useful improvements in filled bag sewing machines, and more particularly to machines of this 15 type which are especially adapted to operate upon small sacks or bags which can be easily fed to the machine by hand.

An object of the invention is to provide a machine of the above character with means for operating the stitching mechanism which 20 shall be simple in construction and readily controlled by the operator so as to stop and start the stitching mechanism.

A further object of the invention is to provide a device of the above character 25 wherein the motor for operating the stitching mechanism is capable of being shifted so as to engage the operating devices for the stitch forming mechanism, or be disengaged therefrom, and when disengaged from said 30 devices, the brake is applied thereto for stopping the stitching mechanism all of which parts are controlled by a treadle accessible to the operator.

A further object of the invention is to 35 provide means whereby the speed of the driving parts of the stitching mechanism may be varied without changing the speed of the motor.

These and other objects will in part be 40 obvious and will in part be hereinafter more fully described.

In the drawings, which show by way of illustration one embodiment of the invention:

45 Figure 1 is a side view of a filled bag sewing machine embodying my improvements, parts thereof being broken away.

Fig. 2 is a plan view of the same.

Fig. 3 is a horizontal sectional view 50 through the yoke and the support therefor showing the adjustable connection between these parts in dotted lines.

Fig. 4 is a sectional view on the line 4—4 of Fig. 3.

The invention consists, generally, in providing a filled bag sewing machine which consists of a main standard on which is adjustably mounted a table or a rest for the bags which are being stitched. At the top of this standard there is a bracket which 55 supports a sewing machine which is connected so as to overhang the support on the standard and the needle reciprocates in substantially a horizontal plane for stitching and closing the mouth of the bag.

The main driving shaft is provided with an enlarged friction disk. The motor for driving the stitching mechanism is mounted in a swinging frame on the bracket and carries a friction wheel adapted to be brought 60 into contact with the friction disk on the main shaft of the sewing machine. The motor frame is swung in one direction by a spring and in the other direction by a treadle. This motor supporting frame is 70 also provided with a brake arm which engages the under face of the friction disk on the main shaft of the sewing machine for stopping the same when released from its driving connection.

80 Referring more in detail to the drawings, my improved filled bag sewing machine consists of a base 1 from which rises a tubular standard 2. At the upper end of the tubular standard there is a bracket 3 which is secured to the standard by suitable bolts 4 which pass through a flange at the lower end of the bracket 3 and a flange at the upper end of the tubular standard 2. The bracket 3 is formed with a base plate 5 which extends slightly above the top of the bracket. A sewing machine 6, which is preferably of the cylindrical bed type is secured to this supporting base plate 5 by suitable bolts 7. The sewing machine as herein 85 shown is provided with a cylindrical bed plate 8 and a depending arm 9. A needle bar 10 reciprocates in said arm and carries a needle 11. The needle bar is reciprocated by a needle lever 12 which is oscillated by 90 a link 13 which cooperates with an eccentric on the main shaft 14 of the sewing machine. A looper cooperates with the needle and is oscillated by a link 15 from the needle lever extension. These parts are of the usual construction.

On the main shaft 14 of the sewing machine is a friction disk 16. This friction

disk is formed with a depending collar 17 which is screwed to the main shaft. The main shaft is also provided with a thrust bearing 18 which carries the end thrust of 5 the shaft. The standard of the machine also carries a bearing roller 19 which is journaled in a bracket 20 screwed to said standard. This roller 19 engages the under face of the friction disk 16.

10 The mechanism of the sewing machine, that is the needle, the looper, and the feeding mechanism thereof, are each operated from the main shaft 14 through a rotation of the friction disk 16. This disk 16 is rotated by an electric motor 21. The outer casing of the motor 21 is formed with projecting lugs 22, see Fig. 2, which are engaged by pivot bolts 23, 23, which pivot bolts in turn are mounted in upwardly projecting 15 arms 24, 24 of a yoke 25. This yoke 25 is adjustably attached to the bracket 3. As herein shown, the yoke at the bottom face thereof has a transverse rib 26, see Fig. 4, which fits in a recess 27 in the upper face of 20 the bracket 3. The bracket 3 is formed with slots 28, 28, and bolts 29, 29 pass through the slots and centrally through the rib 26 and are threaded into the yoke 25.

The armature shaft 30 of the motor carries 30 a friction wheel 31 which overhangs the friction disk 16 above the bearing roller 19. As above noted, the motor is pivotally supported in the yoke 25 so that the friction wheel 31 may be swung toward and from 35 the friction disk 16. A suitable spring 32 is attached at one end to a lug 33 on the motor casing and at the other end to a lug 34 formed integral with the yoke 24. This spring normally swings the motor so as to 40 raise the friction wheel 31 from contact with the friction disk 16.

An arm 35 is made to conform to the motor casing 21 and is secured thereto by suitable screws 36. This arm projects forwardly underneath the armature shaft 30 to a position substantially opposite the friction wheel 31. On the extreme outer end of the arm there is a brake shoe 37. The brake shoe underlies the friction disk 16 and is 45 adapted to engage the under face thereof when the motor is swung on its supporting pivots so as to move the friction wheel 31 out of engagement with the disk. This movement of the motor, which brings the 50 brake shoe into contact with the friction disk 16 is caused by the spring 32. The motor 21 is swung in the opposite direction against the tension of the spring 32 by a treadle 38. This treadle 38 is pivoted at 55 39 at each side of the standard 2 and the treadle arms are connected by a treadle board 40. A rod 41 is attached to one of the arms of the treadle at one end, and at its upper end is attached to a lug 42 formed integral with 60 the arm 35, which is mounted on the motor

casing. This rod 41 is made in two sections, which are adjustably connected together by suitable collars 43, 43.

A casing 44 surrounds the friction wheel 31, except at the side thereof adjacent the 70 friction disk 16 and this casing is provided with suitable supporting arms which are screwed to the arm 35.

Beneath the sewing head there is a support 45 or rest for the bags to be stitched. 75 This support is carried by a sleeve 46 which surrounds the tubular standard 2 and is adjustable up and down thereon to suit different lengths of bags. The sleeve 46 is held in adjusted position by clamping bolts 47, 47, which pass through the sleeve and may be set up against the outer face of the tubular standard 2. To facilitate the turning of the bolts, each bolt is provided with a handle 48. A cord, or other flexible member 80 49, is attached to a lug 50 carried by the sleeve 46, and this member passes over a grooved pulley 51 mounted in a bracket 52 carried by the head of the tubular standard 2. The side of the standard is slotted to 90 permit the placing of the pulley and the passing of the cord or flexible member over the same.

A weight 53 is attached to the lower end of said cord or flexible member and serves 95 to counterbalance the weight of the support or rest 45.

The operation of my device is as follows:

The bags to be stitched are placed on the rest or support 45 and the mouth of the bag 100 directed to the stitching mechanism of the sewing machine. The operator depressing the treadle 38 will swing the motor casing so as to bring the friction wheel 31 into contact with the friction disk 16 and this 105 causes said disk to be operated as the armature shaft rotates. This movement of the motor to bring the friction wheel into contact with the friction disk also moves the brake shoe 37 out of contact with the friction disk and releases the same for free rotation. The downward pressure of the operator on the treadle tends to force the disk 16 downward. The roller or wheel 19 directly underneath the disk forms a support 110 for the disk 16 and takes up this downward thrust. The bearing 18 also serves to relieve the end thrust on the shaft of the sewing machine when the friction wheel is forced into contact with the friction disk. 115 When the bag is stitched, the operator releases the treadle which will permit the spring 32 to at once move the motor casing so as to carry the friction wheel 31 away from and out of contact with the friction 120 disk 16. This movement of the motor casing also causes the brake shoe 37 to engage the under face of the friction disk 16 and stop the rotation of the main shaft of the sewing machine. It will readily be seen, 125 130

therefore, that the stitching mechanism may be thrown into action at the will of the operator very quickly and may be again stopped while the fabric is being properly placed relative to the stitching means. When the treadle is released, the spring 32 normally holds the driving connections separated so that the above mechanism operates automatically to stop the machine and the machine is manually thrown into action.

By releasing the bolts 29 the yoke supporting the motor casing may be shifted toward or from the axis of the disk 16 and may be again secured in adjusted position. This shifting of the yoke and the motor moves the friction wheel 13 either toward or from the center of the disk 16, depending upon the direction of movement of the yoke. When the friction wheel is moved toward the center of the disk, the speed of the sewing machine will be increased and when said friction wheel is moved away from the center of the disk, the speed will be decreased. This permits the varying of the speed of the stitching mechanism for any given speed of the motor. Inasmuch as the spring 32 is connected at one end to the yoke and at the other end to the casing of the motor, this shifting of the parts for varying the speed of the driving mechanism for the sewing machine does not change the tension on the spring.

It will be obvious that minor changes in the details of construction and the arrangement of the parts may be made without departing from the spirit of the invention as set forth in the appended claims.

Having thus described my invention, what I claim as new and desire to secure by Letters Patent is:

1. A filled bag sewing machine including in combination, a standard, a bracket attached to the upper end of the standard, a bag support carried by the standard, a sewing machine mounted on the bracket and overhanging the support, a motor mounted on said bracket, and driving connections between said motor and said sewing machine.

2. A filled bag sewing machine including in combination, a standard, a bracket attached to the upper end of the standard, a bag support carried by the standard, a sewing machine mounted on said bracket and overhanging said bag support, a motor mounted on the upper end of the standard whereby the same may be adjusted transversely of the standard, and driving connections between said motor and said sewing machine including devices whereby an adjustment of the motor varies the speed of the sewing machine.

3. A filled bag sewing machine including in combination, a standard, a bracket attached to the upper end of the standard, a

bag support carried by the standard, a sewing machine mounted on said bracket and overhanging said support, a motor mounted on the upper end of the standard, driving connection between the motor and the sewing machine, means for pivotally supporting said motor, manually controlled means for shifting the motor on its pivotal support for connecting and disconnecting the motor and the sewing machine.

4. A filled bag sewing machine including in combination, a standard, a bracket mounted on the upper end of the standard, a sewing machine carried by said bracket and arranged with its needle in substantially a horizontal line, a filled bag support, a sleeve surrounding the standard and adjustable vertically thereon and carrying said bag support, a motor mounted on said bracket at the upper end thereof, and driving connections between the motor and said sewing machine.

5. A filled bag sewing machine including in combination, a standard, a bracket mounted on the upper end of the standard, a sewing machine carried by said bracket and arranged with its needle in substantially a horizontal line, a filled bag support, a sleeve surrounding the standard and adjustable vertically thereon and carrying said bag support, means connected to the sleeve for counterbalancing the weight thereof and the bag support, and means for holding said sleeve in an adjusted position, a motor mounted on the upper end of the bracket, and driving connections between the motor and the sewing machine.

6. A filled bag sewing machine including in combination, a hollow standard, a sewing machine mounted on the upper end of the standard and overhanging one side face thereof, a sleeve surrounding the standard and adjustable up and down thereon, a bag support carried by the sleeve and extending underneath the sewing machine, a counterweight located within said standard, and a flexible connection between said counterweight and the sleeve for counterbalancing the sleeve and the bag support.

7. A filled bag sewing machine including in combination, a hollow standard, a sewing machine mounted on the upper end of the standard and overhanging one side face thereof, a sleeve surrounding the standard and adjustable up and down thereon, a bag support carried by the sleeve and extending underneath the sewing machine, a counterweight located within said standard, a flexible connection between said counterweight and the sleeve for counterbalancing the sleeve and the support, and screws carried by said sleeve and adapted to engage the standard for holding the sleeve in an adjusted position.

8. A filled bag sewing machine including

in combination, a standard, a bracket secured to the upper end of the standard and having a vertically disposed base plate, a sewing machine secured to said base plate 5 and overhanging one side of the standard, said sewing machine having a needle reciprocating in substantially a horizontal line, a second bracket adjustably secured to the first-named bracket at the upper end 10 thereof whereby said second bracket may be shifted transversely of the standard, a motor mounted on said second bracket, and driving connections between the motor and the sewing machine, said driving connections including devices whereby a movement of the 15 motor and supporting bracket transversely of the standard varies the speed of the sewing machine.

9. A filled bag sewing machine including 20 in combination, a standard, a bracket secured to the upper end of the standard and having a vertically disposed base plate, a sewing machine secured to said base plate and overhanging one side of the standard, 25 said sewing machine having a needle reciprocating in substantially a horizontal line, a second bracket adjustably secured to the first-named bracket at the upper end thereof whereby said second bracket may be shifted 30 transversely of the standard, a motor mounted on said second bracket, driving connections between the motor and the sewing machine, said driving connections including devices whereby a movement of the motor and 35 supporting bracket transversely of the standard varies the speed of the sewing machine, and a bag support arranged beneath the sewing machine and adjustably supported by said support.

40 10. A filled bag sewing machine including in combination, a standard, a bracket secured to the upper end of the standard and having a vertically disposed base plate, a sewing machine secured to said base plate 45 and overhanging one side of the standard, said sewing machine having a needle reciprocating in substantially a horizontal line, a second bracket adjustably secured to the first-named bracket at the upper end thereof 50 whereby said second bracket may be shifted transversely of the standard, a motor mounted on said second bracket, driving connections between the motor and the sewing machine, said driving connections including devices whereby a movement of the motor and 55 supporting bracket transversely of the standard varies the speed of the sewing machine, said motor being pivotally connected to its supporting bracket, and means for swinging 60 the motor on its pivot for connecting and disconnecting the motor and sewing machine.

11. A filled bag sewing machine including 65 in combination, a standard, a bracket secured to the upper end of the standard and

having a vertically disposed base plate, a sewing machine secured to said base plate and overhanging one side of the standard, said sewing machine having a needle reciprocating in substantially a horizontal line, 70 a second bracket adjustably secured to the first-named bracket at the upper end thereof whereby said second bracket may be shifted transversely of the standard, a motor mounted on said second bracket, driving connections between the motor and the sewing machine, said driving connections including devices whereby a movement of the motor and supporting bracket transversely of the standard varies the speed of the sewing machine, 80 said motor being pivotally connected to its supporting bracket, a spring for swinging the motor on its supporting pivot for disconnecting the motor from the sewing machine, and treadle connections for 85 swinging the motor in the opposite direction and connecting the same to the sewing machine.

12. A filled bag sewing machine including in combination, a standard, a bracket secured to the upper end of the standard and having a vertically disposed base plate, a sewing machine secured to said base plate and overhanging one side of the standard, said sewing machine having a needle reciprocating in substantially a horizontal line, 90 a second bracket adjustably secured to the first-named bracket at the upper end thereof whereby said second bracket may be shifted transversely of the standard, a motor mounted on said second bracket, driving connections between the motor and the sewing machine, said driving connections including devices whereby a movement of the motor and 95 supporting bracket transversely of the standard varies the speed of the sewing machine, and a bag support arranged beneath the sewing machine and adjustably supported by said support.

105 13. A filled bag sewing machine including in combination a standard, a bag support removably mounted on said standard, a sewing machine mounted on the standard and overhanging the support, a motor adjustably mounted at the upper end of the 110 standard, and driving connections between the motor and the sewing machine, a sleeve adjustably mounted on said standard, a bag support carried by the sleeve and extending 115 underneath the sewing machine, means for counterbalancing said sleeve and bag support, and means for holding the sleeve in adjusted position on the standard.

120 14. A filled bag sewing machine including in combination a standard, a filled bag support adjustable vertically on the stand- 130

ard, means for holding the bag support in an adjusted position, a sewing machine mounted on the upper end of the standard and overhanging said filled bag support, and 5 a horizontal driving shaft at the upper end of the standard for driving said sewing machine.

15. A filled bag sewing machine including in combination a standard, a filled bag 10 support adjustable vertically on the standard, means for holding the bag support in an adjusted position, a sewing machine

mounted on the upper end of the standard and overhanging said filled bag support, a motor mounted on the upper end of said 15 standard, and driving connections between the motor and said sewing machine.

In testimony whereof, I affix my signature in the presence of two witnesses.
